(57) **CLAIM**

The ornamental design for a traction device, as shown and described.

DESCRIPTION

FIG. 1 is a front top perspective view of a traction device showing my design attached to a shoe in broken lines;

FIG. 2 is a top plan view thereof;

FIG. 3 is a bottom plan view thereof;

FIG. 4 is a side view thereof;

FIG. 5 is another side view thereof;

FIG. 6 is a front view thereof; and,

FIG. 7 is a back view thereof.

The broken lines shown in the drawings represent portions of the traction device that form no part of the claimed design. All surfaces not shown form no part of the claimed design.
